UNITED STATES PATENT OFFICE.

HENRY WATSON, OF NEWPORT, WALES.

DEVICE ADAPTED FOR SHARPENING THE BLADES OF SAFETY RAZORS.

Application filed March 2, 1921. Serial No. 449,074.

To all whom it may concern:

Be it known that I, HENRY WATSON, a subject of the King of Great Britain and Ireland, and residing at 212 Stow Hill, 5 Newport, in the county of Monmouth, Wales, have invented certain new and useful Improvements in and Relating to Devices Adapted for Sharpening the Blades of Safety Razors, of which the following is

10 a specification.

This invention relates to devices adapted for sharpening the blades of safety razors, of the kind in which the blade is operated on by a pair of rollers mounted in a frame 15 and making rolling contact one with another, and a bar having a slot therein is mounted at its ends in the sides of the frame on an axis intermediate between the axes of the rollers for the purpose of guiding the blade.

20 In the specification of my British application for Letters Patent No. 143,335 I have indicated that steel rollers, hardened or not, may be employed for sharpening razor blades, and in devices in accordance with the present invention rollers of this material are preferably employed.

The object of the present invention is to 30 provide a device of the kind referred to, having improved means adapted to guide and limit the motion of the blade in accordance with the angle of the cutting edge thereof.

According to the invention the bar which 35 is provided with a slot adapted to accommodate the blade to be operated upon, of greater width than the maximum thickness of the blade, is pivotally mounted in the frame and is associated with means adapted 40 to secure the bar in the position into which it is rotated about its axis.

A device in accordance with the invention is illustrated by way of example in the accompanying drawings, in which:—

45 Figure 1 is an elevation partly in section of the device, and

Figure 2 a cross section thereof.

In the drawings 1 and 2 are the rollers pivoted respectively in collars 3, 3^a and 4, 4^a, 50 secured in slots in the sides 5 and 5^a of the frame, of which 6 is the base, screws 7 and 7^a being provided for regulating the pressure between the rollers which are rotated by means of the crank handle 8 secured to the 55 pivot of the upper roller and driving through the spur wheels 9 and 9^a the lower roller.

A bar 10 provided with a slot 11 and with pivots 12 and 13 is secured by these pivots in holes in the sides of the frame, a clamping nut 14 being mounted on the screwed 60 pivot 13 and serving to secure the slotted bar in the desired position, the projection 15 on the bar being provided to facilitate its adjustment.

When the slotted bar is in the position 65 shown in dotted line in Figure 2, as will be observed, the blade cannot be moved at all, while when the bar is in the position shown in full line the blade 16 may be moved through the maximum angle. Obviously, 70 therefore, by arranging the bar in any position intermediate between the positions indicated the outer edge of the blade may be moved by hand, by raising or lowering the outer edge of the blade, through any angle 75 less than the maximum and in this way the device may be adjusted to limit the angle through which the outer edge of the blade may be moved, in order to permit of blades having cutting edges of different angles 80 being operated upon satisfactorily.

The frames of the devices are conveniently provided with means whereby they may be attached to a table or the like when in use.

85 In use, a small quantity of a suitable abrasive or polishing composition is preferably applied to the surface of the rollers and the handle is turned so as to cause the rollers to rotate in the direction indicated by 90 the arrows in Figure 2.

Having now described my invention, what I claim as new and desire to secure by Letters Patent is:—

A device adapted for sharpening the 95 blades of safety razors comprising a frame, a pair of sharpening rollers mounted in the frame and making rolling contact one with another, a bar pivotally mounted at its ends in the sides of the frame on an axis intermediate between the axes of the rollers, said 100 bar having a slot of a width greater than the maximum thickness of the blade, and means whereby the bar may be secured in any position into which it is rotated about 105 its axis to vary the angle through which the blade engaged within the slot may be moved during sharpening.

In testimony whereof I have signed my name to this specification.

HENRY WATSON.
